FIGURE TRUNDLE TOY

Herman G. Fisher, Walter P. Doe, and
Leslie W. Sly, East Aurora, N. Y.

Application November 20, 1951, Serial No. 17,477

Term of patent 14 years

(Cl. D34—15)

To all whom it may concern:

Be it known that we, Herman G. Fisher, Walter P. Doe, and Leslie W. Sly, citizens of the United States, residing at East Aurora, State of New York, have invented a new, original, and ornamental Design for a Figure Trundle Toy, of which the following is a specification, reference being had to the accompanying drawing, forming a part hereof.

Fig. 1 is a perspective elevational view of a figure trundle toy, showing our design; and

Fig. 2 is a top plan view thereof.

The side of the figure trundle toy not shown has substantially the same appearance as the side shown in Fig. 1.

We claim:

The ornamental design for a figure trundle toy, as shown and described.

HERMAN G. FISHER.
